CLAIM

The ornamental design for portable electric tool vac, as shown and described.

DESCRIPTION

FIG. 1 is a top perspective view of a portable electric tool vacuum showing our new design;

FIG. 2 is a right end elevational view thereof;

FIG. 3 is a left end elevational view thereof;

FIG. 4 is a front elevational view thereof;

FIG. 5 is a left elevational view thereof;

FIG. 6 is a top plan view thereof; and,

FIG. 7 is a bottom plan view thereof.

The electric cord shown in broken lines in FIGS. 1 and 4-7 is shown for illustrative purposes only and forms no part of the claimed design.
